DESIGN FOR A MICROPHONE

Chauncey E. Waltman, Chicago, Ill., assignor to
Shure Brothers Inc., Chicago, Ill., a corporation
of Illinois

Application June 13, 1947, Serial No. 139,654

Term of patent 14 years

(Cl. D26—14)

To all whom it may concern:

Be it known that I, Chauncey E. Waltman, a citizen of the United States, residing at Chicago, in the county of Cook and State of Illinois, have invented a new, original, and ornamental Design for Microphone, of which the following is a specification, reference being had to the accompanying drawing, forming a part thereof in which:

Figure 1 is a perspective view of a microphone showing my new design;

Fig. 2 is a front elevational view thereof on a somewhat larger scale;

Fig. 3 is a side elevational view thereof on the same scale as Fig. 2; and

Fig. 4 is a top plan view thereof on the same scale as Figs. 2 and 3.

I claim:

The ornamental design for a microphone, substantially as shown.

CHAUNCEY E. WALTMAN.
